UNITED STATES PATENT OFFICE.

ARCHELAUS E. SPENCER, OF CHICAGO, ILLINOIS.

BLUING-PADDLE.

SPECIFICATION forming part of Letters Patent No. 251,384, dated December 27, 1881.

Application filed May 11, 1881. (No model.)

To all whom it may concern:

Be it known that I, ARCHELAUS E. SPENCER, a citizen of the United States, residing at Chicago, in the county of Cook and State of Illinois, have invented certain Improvements in Bluing-Paddles; and I do hereby declare that the following is a full, clear, and exact description of the invention, which will enable others skilled in the art to which it appertains to prepare the same.

This invention has for its object to provide an improved means of preparing bluing and applying it to laundry purposes, whereby it can be conveniently employed to give the required tint to the water for bluing clothes and other articles.

Heretofore it has been customary to employ the bluing in the form of lumps, powder, or in solution; but in each case serious inconveniences have been encountered. When in the form of lumps the process of solution is slow and tedious, involving delay and loss of time. When in the form of powder great waste occurs, as the powder is liable to be scattered in using the bluing, and, besides, is liable to discolor and injure surrounding objects with which it may come in contact. When in solution it requires to be kept in bottles, which are liable to accidental breakage, especially in cold weather, when the solution freezes. Moreover, when employed either in powder or solution inclosing packages or receptacles are required, which is a considerable item of expense.

Paper has been impregnated or coated with bluing and employed in suitably-sized pieces to impart the desired tint to the water; but such I do not claim.

Heretofore coloring-matter has been packed in a recess formed in the end of a handle, the coloring-matter being housed therein by a covering of textile material; but such differs from my invention, as will hereinafter appear.

My invention is designed to improve upon the above-enumerated means of putting up bluing and provide a means whereby the bluing can be put up, as a new article of manufacture, in such form as to be readily applied to the water with perfect uniformity and in the exact quantities necessary to give any tint or depth of color thereto.

To this end my invention consists in applying the bluing upon the surface of a strip or paddle of rigid material—such as wood—leav-

ing a portion thereof free to serve as a handle, by means of which the paddle may be manipulated.

In the drawings, Figure 1 represents a perspective view of a paddle, showing my invention applied thereto. Fig. 2 represents a sectional view of the same.

The letter A indicates a paddle, constructed preferably of soft wood, and provided with a handle, B, by which it may be manipulated. The said handle is provided with an aperture, C, by which the device may be suspended from a suitable support. The lower part or blade of the paddle is coated with bluing by placing it in a solution of the same until coated or saturated, and then removing it and allowing it to dry.

When an additional quantity of bluing is required upon the paddle it may be redipped after drying, so as to allow the coloring-matter to form an additional coating thereon; and in order to prevent the coating from cracking and chipping off, some mucilaginous material is dissolved in the solution previous to applying it to the paddle. I have found, in practice, that dextrine answers well for the purpose, and it is employed in the proportion of a quarter of a pound to a gallon of solution.

In using my improved device the water is simply stirred by the paddle, which gives off its color quickly and with perfect uniformity, and to any desired depth, depending upon the length of time the stirring is continued. When the proper tint is obtained the paddle is hung up to dry, after which it is ready for use again.

The paddle may be used over and over again until the coloring-matter is completely exhausted, there being no waste of any consequence.

Any of the coloring-matters employed for bluing purposes may be used in connection with my invention, and hence I do not limit myself to any particular material or compound.

What I claim is—

As a new article of manufacture, a paddle having a portion of its surface coated with bluing, substantially as and for the purpose specified.

ARCHELAUS E. SPENCER.
